The ornamental design for a translucent octopus-shaped nightlight, as shown and described.

DESCRIPTION

FIG. 1 is a perspective view of the ornamental design for a translucent octopus-shaped nightlight, as seen from the front, left side;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a perspective view of the ornamental design for a translucent octopus-shaped nightlight with a watch mounted on the octopus shaped nightlight, as seen from front, left side.

The broken lines showing the eye of the octopus and the connectors in FIGS. 1, 2, 4-7 represent portions of the article which form no part of the claimed design. The broken lines showing the watch in FIG. 7 are included for the purpose of illustrating environmental structure and form no part of the claimed design.
